ATTORNEY

UNITED STATES PATENT OFFICE.

WILLIAM F. MUIR, OF FRESNO, CALIFORNIA.

DRAIN BOARD FOR SINKS.

Application filed March 13, 1922. Serial No. 543,501.

To all whom it may concern:

Be it known that I, WILLIAM F. MUIR, a subject of the King of Great Britain, having declared my intention of becoming a citizen 5 of the United States, residing at Fresno, in the county of Fresno and State of California, have invented certain new and useful Improvements in Drain Boards for Sinks, of which the following is a specification.

10 My invention relates primarily to a combined drain board and apron for sinks, and the object thereof is to provide a device of that character of a unit or knocked down construction which can be easily and quickly 15 assembled and positioned for use.

A further object is to provide, in a device of the above character, means for producing water tight joints between the various units thereof.

20 A still further object is to provide a device of the above character having an outer exposed face of metal which may be enameled or otherwise ornamented and a body of a plastic composition such as concrete, 25 clay, or the like.

Other objects and advantages will appear hereinafter and, while I have shown and will describe the preferred form of my device, I wish it to be specifically understood 30 that I do not limit myself to such preferred form, but that various changes and adaptation may be made therein without departing from the spirit of my invention.

In the drawings accompanying and forming 35 a part hereof;

Fig. 1 is a perspective view of the preferred form of my device.

Fig. 2 is a diagrammatic front elevation of my device.

40 Fig. 3 is a section on the line 3—3 of Fig. 1.

Fig. 4 is an enlarged sectional detail of a portion of Fig. 3.

Fig. 5 is a section on the line 5—5 of Figs. 45 1 and 9.

Figs. 6 and 7 are enlarged sectional views of portions of Fig. 5.

Fig. 8 is an enlarged sectional elevation on the line 8—8 of Figs. 1 and 9.

50 Fig. 9 is a perspective elevation of another form of my device.

Fig. 10 a section on the line 10—10 of Fig. 9.

55 Fig. 11 is a section on the line 11—11 of Fig. 9.

Figs. 12 and 13 are a fragmentary top

plan and front edge elevation perspective of a portion of my device.

Fig. 14 is a diagrammatic front elevation 60 of another form of my device.

Fig. 15 is a left-hand end elevation of the parts shown in Fig. 14.

Fig. 16 is an enlarged fragmentary detail 65 of another form of my invention.

Referring to the drawings my device 70 which comprises a back member or apron 15, provided with ears 16 by means of which said apron is secured in position upon the wall, the ends of which apron rest upon the inner edge of the drain boards 17 and 18, 75 and the portion 19 of which projects downwardly and rests upon the upper face of the rim of the sink 20^a at the rear. Drain boards 17 and 18 are provided with the usual drain grooves 20 and 21. Apron 15 is provided 80 centrally of its length with a soap recess 22 and apertures 23 and 24 through which the usual faucets project. The front edges of drain boards 17 and 18 are connected by a cross member 25 which rests upon the upper face of the rim of 20 at the front edge thereof. Members 25 and drain boards 17 85 and 18 are connected together by means of dowel pins 26 and 27 as best shown in Figures 12 and 13.

In the construction of members 15, 17, 18 and 25 the outer faces 28 are formed preferably from sheet metal pressed into shallow troughs of the desired configuration and members 17, 18 and 25 have their interiors 90 filled with plastic composition 29, such as concrete or the like tie members 30 being provided on the inner face of said members to hold said plastic composition positioned 95 therein. Extending along the lower edge of member 15 for a distance equal to the length of members 17 and 18 is a semi-circular recess 31 which is adapted to surround bead 32 provided in the inner edge of members 17 and 18 but being spaced therefrom and this space is filled with a plastic material, such as putty, which provides water tight joint 100 between said members, as best shown in Figures 3 and 4. Extending along the lower edge of central portion 19 of member 15 is a semi-circular recess 34 which rests upon the upper face of the rim of the sink 20, which recess is filled with a plastic material such as putty and provides a water tight joint therebetween. A similar joint 105 35 is provided between the contacting faces of members 17 and 18 and sink 20.

In positioning my device the usual framework for the sink is provided. The sink is placed in position thereon, it being understood that a recess will be provided for the 5 rim of the sink, whereby the upper face of the sink will be parallel with the upper edges of the support. Member 25 is then positioned upon the front edge of the rim of the sink. Members 17 and 18 are then 10 positioned thereon, the dowel pins 26 and 27 being projected in the apertures in members 17 and 18 to lock the same together, and expansion bolts or screws or any other suitable fastening devices are used to secure 15 members 17 and 18 in the desired position to hold the same against accidental displacement. The recess in the lower edge of member 15 is then filled with putty or any other suitable material and member 15 is then 20 positioned with its lower end resting upon the bead 32 and pressed downwardly until a tight joint is formed between member 15 and members 17 and 18 and sink 20. Suitable fastening means such as screws, nails, 25 or the like are then projected through holes 37 in ears 16 into the wall to hold the upper edge of member 15 securely positioned.

In the form shown in Figures 9, 10 and 11 my construction is essentially the same as 30 in the preferred form with the exception that the drain boards and its component part of the apron are formed from a single piece and the portion bridging the distance between and across the sink is formed separately, water tight joint being provided between the abutting edges thereof as best shown in Fig. 11, otherwise the construction is the same.

In the form shown in Figs. 14 and 15 the 40 construction is essentially the same with the exception that each drain board has its own individual apron formed separately and a separate portion is provided for the sink, water tight joints being provided between 45 the contacting portions as hereinbefore explained. The object of this construction being to provide a device which may be varied or adjusted to suit varying conditions such as the length of the sink and the width and 50 length of the drain boards.

In Fig. 16 is shown another method of forming a water tight joint surrounding the sink. In this form I provide the sink 55 20^a with an upstanding rim 20^b around the outer edge thereof and in the undersides of members 17, 18 and 25 and the lower edge of member 19, I provide a recess 28^a within which the rim 20^b is positioned, the recess 28^a being first filled with cement or putty.

60 Having described my invention what I claim is:

1. A drain board for sinks and the like comprising a back member adapted to be mounted parallel with a wall; ears projecting upwardly from the upper edge of said

back member; a relatively narrow downwardly depending portion centrally of the lower edge of said back member; and an arcuate downwardly opening trough extending longitudinally of the lower edge of said back member. 70

2. The combination with a sink of an apron and drain boards therefor, said apron and drain boards being in cross section substantially shallow troughs opening downwardly and rearwardly, the abutting edges of said members being provided with cement holding troughs whereby the connections therebetween are made water tight. 75

3. The combination with a sink of a back 80 apron and drain boards, said drain boards being mounted at their inner ends on the edges of said sink to extend parallel therewith, the abutting edges of said drain boards being provided with arcuate troughs adapted 85 to be filled with cementitious material, said back apron having its central portion resting upon the rear edge of said sink and its end portions cut away to rest upon the upper face of said drain board, said sink and drain 90 boards abutting surfaces being provided with longitudinally extending troughs adapted 95 for holding cementitious material; a connection between the front edges of said drain boards resting upon the front edge of said sink, all of said members being in cross section of substantially inverted shallow trough shapes and being filled with plastic material; holding lugs secured to the inner face of the 100 body portion of said back apron and drain boards adapted for retaining said plastic material against displacement. 100

4. A drain board for sinks and the like comprising a substantially rectangular inverted pan-shaped body member adapted to 105 be mounted at one end upon one end of a sink to extend parallel therewith, said supporting end being provided with a downwardly opening shallow trough along its entire length adapted to be filled with cementitious material; a plastic filling for said body member, and retaining means secured to the inner face of said body member adapted for retaining said plastic filling against displacement. 110

5. A drain board for sinks and the like comprising in combination a sink; a supporting frame for said sink; a drain board at each side of said sink extending outwardly therefrom; an apron extending upwardly 115 from the rear edge of said sink and having cut away portions adapted to rest upon the upper face of the said drain boards. 120

6. A drain board for sinks and the like comprising the combination of a sink; a supporting frame therefor; a drain board extending from each end of said sink to the ends of said supporting frame; means between said drain boards and frame for detachably securing the same in position for use, the ends of said boards resting upon said 125 130

- 5 sink being provided with downwardly opening arcuate troughs longitudinally thereof adapted to be filled with cementitious material; an apron having the central portion of its lower edge resting upon the rear edge of said sink and being provided at its lower edge with a longitudinally extending, downwardly opening, trough adapted for filling with a cementitious material, the ends of said 10 apron being narrowed at their lower edges to form a recess for the reception of the inner edges of said drain boards and being provided with longitudinally extending, downwardly opening, recesses; upwardly extending 15 tongues on the said edges of said drain boards adapted to project into the recesses in the apron, the space between said tongues and recesses being adapted for filling with cementitious material.
- 20 7. The combination with a sink of a back apron and drain boards, said drain boards being mounted at their inner ends on the edges of said sink to extend parallel therewith, the abutting edges of said drain boards 25 being provided with arcuate troughs adapted to be filled with cementitious material, said back apron having its central portion resting upon the rear edge of said sink and its end portions cut away to rest upon the upper face of said drain board and being 30 provided with a forwardly opening recess centrally of the face thereof, said apron and drain boards abutting surfaces being provided with longitudinally extending troughs adapted for holding cementitious material; 35 a connection between the front edges of said drain boards resting upon the front edge of said sink, all of said members being in cross section of substantially inverted shallow trough shapes and being filled with plastic 40 material; holding lugs secured to the inner face of the body portion of said back apron and drain boards adapted for retaining said plastic material against displacement.
- 45 In witness that I claim the foregoing I have hereunto subscribed my name this 10th day of October 1921.

WILLIAM F. MUIR.
